UNITED STATES PATENT OFFICE.

GÜNTHER KLAHRE, OF BERLIN, GERMANY, ASSIGNOR TO GENERAL ELECTRIC COMPANY, A CORPORATION OF NEW YORK.

INCANDESCENT-ARC DEVICE.

Application filed July 28, 1924. Serial No. 728,530.

To all whom it may concern:

Be it known that I, GÜNTHER KLAHRE, a citizen of Germany, residing at Berlin, Germany, have invented certain new and useful

5 Improvements in Incandescent-Arc Devices, of which the following is a specification.

The present invention relates to devices in which an arc-like discharge is operated in an inert gas between refractory electrodes 10 and is particularly concerned with the starting of the discharge between said electrodes by contact and separation of electrode members.

In devices of this type which are provided 15 with contact starting mechanism, a separation of the electrodes usually is effected by a thermostatic member, which, when heated, draws the electrodes apart with the resulting formation of an arc. To insure positive 20 contact between the electrodes, when the arc is not operating and to prevent the anode from being drawn away from the cathode prematurely, the anode heretofore has been arranged to press against the 25 cathode when the device was not operating. As a result of this condition the electrodes tended to remain in contact for several seconds, while current passed through them. Because of the high current density at the 30 points of contact it often happened that the anode became welded or "frozen" to the cathode before the thermostatic starting device could exert sufficient force to separate the electrodes. As a result the thermostatic 35 device sometimes was unable to separate the electrodes and in that event the device was rendered inoperative.

According to the present invention a construction is provided whereby a positive 40 starting of an arc lamp, or other device, is attained without any danger of welding of the electrodes. This result is obtained by providing a resiliently supported stop or motion-limiting device, against which the 45 movable electrodes will bear, and from which it will be separated preferably with a rubbing contact when the arc is started. This stop device is conductively connected with the opposite electrode, preferably the 50 cathode, so that when the movable electrode, in the preferred case the anode, is separated from the stop device, an arc will be started which will later be transferred to the electrode to which the stop device is 55 connected.

The novel feature in my invention will be explained in greater detail in connection with the accompanying drawing in the following specification.

In the drawings Fig. 1 illustrates a lamp 60 embodying my invention, Fig. 2 shows the position of the stop plate and electrodes; when the arc is operating, and Figs. 3, 4, 5 and 6 illustrate modifications of my invention.

The lamp shown in Fig. 1 comprises a glass bulb *a* containing an inert gas, such as argon, neon, nitrogen and provided as usual with a screw base *j*, to which the leads *c* and *d* are conductively connected.

The electrodes and starting mechanism are carried by a glass stem *b* into which the leads *c* and *d* are sealed in the usual manner. The bar-shaped cathode *e*, which preferably consists of tungsten, and which may be provided with a coating of thorium or other oxide, is supported upon the stem *b* by wires *f* and *g*. The anode *h* has been shown as of spherical shape, although of course it may assume other forms. The anode which preferably also consists of tungsten is carried by a support *i*, which is mounted upon the stem *b* of the lamp through the intermediary of a thermostatic or bi-metal strip *k*, which, when heated, becomes bent and moves the anode in order to start the arc. When the arc is not operating the anode *h* rests against a stop plate *l* which in Fig. 1 is mounted upon a springy or resilient holder *m*, which in turn is fastened to the cathode support *f*. A resistor wire *n* serving as the starting resistance is held by the radial supports *w* arranged around the stem of the lamp and is connected to the terminals of the lamp in series with the electrodes, the circuit being from the leading-in conductor *d* through the resistor wire *n*, a support *v*, the anode stem *i*, the stop plate *m*, the cathode support *f* to the opposite leading-in conductor *c*. One portion of the resistor *n* is arranged as indicated by *o* approximately parallel to the bi-metal strip *k*, so that when the lamp is switched on the thermostatic strip *k* is not only heated by current passing there-through, but also by heat radiated from the resistor *o* and hence is caused to separate the anode *h* from the stop plate *l*. This separation occurs by a curved motion about the support of the anode in the direction of the

arrow *x*. For some distance the anode is followed in its motion by the spring supported stop plate or until the stop plate strikes the end of the cathode as shown in 5. 2. During the brief period of simultaneous motion of the anode and the stop plate, the anode slides somewhat upwards on the surface of the stop plate and therefore the anode does not remain long enough in contact at one particular point to permit welding. The distance between the stop plate and the cathode is so adjusted that the arc is formed by the separation of the anode and the stop plate at the instant of contact 10 of the stop plate with the cathode. Hence, the arc immediately jumps over to the cathode. The anode may continue to move in the direction indicated by the arrow through the action of the thermostatic support until it remains in the position shown in Fig. 2, being separated from the cathode by a distance suitable for the operation of the arc. The stop *l* preferably consists of a polished tungsten plate to facilitate the 15 sliding of the arc upon its surface in order to prevent displacement of the anode and the stop plate especially during transportation of the lamp. A loop-shaped guide *p* surrounding the anode support *i* is mounted 20 upon the stem *b*.

Various modifications in the construction of the stop plate *l* can be used. As shown in Fig. 3 the limit stop may consist of a semi-spherical body *l'*, which is threaded directly 25 upon the bar-shaped cathode *c*, a spiral spring *q*, surrounding the cathode, being provided to hold the stop against the anode *h*. A forward travel of the stop *l* is limited by a check *r*, but it is possible to omit the 30 check *r* in the case the spring tension is correctly chosen. The different positions of the stop *l* and the anode *h* during starting are indicated by dotted lines in Fig. 3.

Although the cathode has been shown for 35 illustrative purpose in Figs. 1 and 3 as consisting of a bar, it may assume various other shapes. In Figs. 4 and 5 a block-shaped cathode *s* has been illustrated. In this case also the resilient supported stop plate *l* may 40 assume a resting position against the cathode *s* during the operation of the arc, although of course the forward travel of the stop plate may be limited by check as already shown in Fig. 3.

55 In Fig. 6 a construction has been shown in which the resiliency of the stop *l* is secured by making the supports *j*, *g* of the cathode yielding. As shown in Fig. 6 flat springs *t* are inserted in the cathode supports, the stop plate *l* being in this case an integral part of the cathode structure. When the anode *h* is drawn in the direction of the arrow by the action of the thermostatic support, the cathode structure first 60 follows the motion of the anode. The anode 65

slides over the stop plate *l* and finally is separated therefrom, the arc springing over to the cathode proper and operating as already described.

What I claim as new and desire to secure 70 by Letters Patent of the United States, is:—

1. An arc device comprising the combination of a cathode, an anode, a thermostatic support for said anode, and a yielding conductive stop member connected to said 75 cathode and located to engage with said anode when said device is not operating.

2. An arc device comprising the combination of a cathode adapted to be operated at incandescence, a cooperating anode, a yielding conductive stop member connected to one of said electrodes and engaging when said device is not operating with the cooperating electrode, and means for drawing said cooperating electrode away from said member 80 to strike an arc when the device is to be started.

3. An arc device comprising the combination of an incandescent cathode, a cooperating anode, a yielding conductive member 90 connected to said cathode, and engaging when said device is not operating, with said anode, a thermostatic support for said anode, and means for generating heat when said device is to be started to cause said anode to 95 leave said stop member.

4. An arc device comprising the combination of a tungsten cathode, a cooperating anode, a stop member, consisting of a smooth plate of refractory metal and a springy support, applied in said device to cause said plate to bear against said anode when the device is not operating, temperature-responsive means for separating said anode and stop member and a resistor arranged to 100 thermally actuate said separating means.

5. An incandescent arc lamp comprising the combination of a tungsten cathode (*c*), a cooperating anode (*h*), a bi-metal support (*k*) for said anode, a mechanical limit stop 110 bearing against said anode which comprises a smooth plate (*l*) and a resilient holder (*m*), a support (*f*) positioned to hold said stop against said cathode when the lamp is operating, means for heating said bi-metal support to cause the anode to leave said stop and to strike an arc, an enclosing envelope (*a*) and an inert gas filling therein.

6. An electric lamp comprising a sealed bulb, a gaseous filling therefor, cooperating electrodes of refractory metal, a yielding conductive stop member connected to the cathode, spaced away therefrom and located to engage with the anode when the device is not operating and means for separating 120 said anode from the stop member with a rubbing motion when the lamp is to be lighted.

In witness whereof, I have hereunto set my hand this 7th day of July, 1924.

GÜNTHER KLAHRE.
